ABSTRACT

A dimensionally stabilized microporous polyamide membrane having enhanced flow characteristics comprised of a film forming organic polymeric material of low shrinkage prepared by drying the membrane, under conditions of restraint in the plane of the membrane to

minimize the shrinkage until the membrane is essentially in a dried condition. A process is also described for preparing a microporous membrane designed to enhance incorporation and retention of a charge modifying resin for use as a charge modified filter media. The process comprises preparing a dope solution of a film forming polymer in a solvent system, directly casting the solution under the surface of a quenching medium comprising a non-solvent system for the polymer for a time sufficient to form micropores in the film, and drying the film while controlling the planar dimensions of the film during the drying.

The foregoing process is particularly useful in the preparation of a charge modified membrane of enhanced electrokinetic capture potential in the filtration of charged submicronic contaminants from aqueous liquids.
